UNITED STATES PATENT OFFICE.

FREDERICK D. CASEY, OF NORTH WATER GAP, PENNSYLVANIA.

SPARK-PLUG ATTACHMENT.

No. 902,373.

Specification of Letters Patent.

Patented Oct. 27, 1908.

Application filed July 25, 1907. Serial No. 385,457.

To all whom it may concern:

Be it known that I, FREDERICK D. CASEY, a citizen of the United States, and a resident of North Water Gap, in the county of 5 Monroe and State of Pennsylvania, have invented a new and Improved Spark-Plug Attachment, of which the following is a full, clear, and exact description.

This invention relates to spark plug attachments and more particularly to those which are used in connection with the engines of motor boats and vehicles, and it is efficient in operation and inexpensive to manufacture.

15 The object of this invention is to provide covers for the spark plugs of engines, to prevent water or moisture from reaching the electrical connections on the spark plugs and thereby causing a short circuit.

20 A further object is to prevent the possibility of electrical shocks and to lengthen the life of the spark plug by protecting it from moisture and other injurious substances.

25 The invention consists in the construction and combination of parts to be more fully described hereinafter and particularly set forth in the claim.

Reference is to be had to the accompanying drawings forming a part of this specification, in which similar characters of reference indicate corresponding parts in both the views, in which

35 Figure 1 is a longitudinal section of the device showing the same attached to an engine; and Fig. 2 is a perspective view of the spark plug attachment.

Before proceeding to a more detailed explanation of my invention, it should be 40 understood that water or other moisture frequently collects on the spark plugs of an engine, especially those engines which are used in motor vehicles or boats. This is very apt to cause a short circuit and interfere with the proper operation of the engine.

45 To provide a spark plug cover of efficient form and simple construction and at the same time capable of obviating all danger of short circuits, I provide a dome-shaped casing having a detachable base which is adapted to be suitably supported in position at a spark plug.

50 Referring more particularly to the drawings, 3 represents the spark plug casing, which is preferably fashioned from metal or other similar suitable material. I provide a

detachable base 6 of suitable material, such as brass, or other metal, and approximating in shape the cross sectional form of the casing. The latter is firmly arranged upon the 60 base, the rim of the casing peripherally engaging the base and being held in position by frictional engagement therewith.

The spark plug is provided with the usual stem 1, which together with the collars 4, 65 and a thumb nut 2, constitutes a binding post, by means of which a conductor 5 is detachably connected with the spark plug. The conductor 5 enters the casing through an aperture 10. This aperture may be either 70 in the casing or in the base, whichever is the more convenient for use. The base 6, has a threaded opening by means of which it can be removably mounted upon the correspondingly threaded base 7 of the spark 75 plug. Although as shown in the accompanying drawings, this base 6 is supported on the threaded base 7 of the spark plug, other suitable means for supporting the base 6, may be employed. For example, the base 6 80 may be formed integral with the spark plug.

It will be understood that my invention can be used in connection with spark plugs of different types, and that the form of the 85 spark plug is not an essential feature of the device. The underlying principle consists in providing a suitable casing for protecting the spark plug from moisture or other foreign substances liable to interfere with the 90 operation thereof, and suitable means for arranging the casing at a spark plug. The casing may be dome or globular-shaped, though the specific form is not essential to my invention.

Having thus described my invention, I claim as new and desire to secure by Letters Patent:

The combination with a spark plug, of a disk detachably connected therewith, and a 100 cover for the plug, the edge of the cover frictionally engaging the edge of the disk, whereby to retain said cover in place, said cover having an opening to permit the passage of a conductor.

105 In testimony whereof I have signed my name to this specification in the presence of two subscribing witnesses.

FREDERICK D. CASEY.
